UNITED STATES PATENT OFFICE.

DAVID MEIN NESBIT AND WALTER CLOWES, OF LONDON, ENGLAND; SAID CLOWES ASSIGNOR TO SAID NESBIT.

WATER HEATER AND SEPARATOR.

SPECIFICATION forming part of Letters Patent No. 614,743, dated November 22, 1898.

Application filed June 27, 1898. Serial No. 684,620. (No model.)

To all whom it may concern:

Be it known that we, DAVID MEIN NESBIT and WALTER CLOWES, engineers, residing at 12 Great James street, Bedford Row, London, W. C., in the Kingdom of England, subjects of the Queen of Great Britain and Ireland, have invented certain new and useful Improvements in Water Heaters and Separators, (for which we have made applications for patent in Great Britain, No. 21,020, dated September 13, 1897, and No. 12,007, dated May 26, 1898,) of which the following is a specification.

This invention relates to improvements in combination feed-water heaters and condensers in which exhaust or waste steam is employed to heat the feed-water supply for boilers or for like purposes, the object of our invention being to eject the air from the receiver and to automatically regulate the employment of the feed-water for condensing the steam and for supplying the boiler and to utilize the outer portion of the heater-chamber as a settling-box or baffling-chamber through which the steam can flow and deposit some of its impurities before entering the boiler.

In the four accompanying sheets of explanatory drawings, Figure 1 is a vertical longitudinal section through my improved heater and condenser. Fig. 2 is a sectional plan of the under side of my heater-chamber, showing the exhaust-steam-inlet chamber and the sparge or condensing spray-pipe in position. Fig. 3 is a sectional plan of the upper portion of my chamber, showing the tubes in section and with the outer jacket or settling-box or casing removed. Fig. 4 is a sectional plan showing the outer casing or settling-chamber and showing the ribs or baffling-blades arranged upon the exterior of the upper water-chamber and also upon the interior of the surrounding outer casing or jacket of the settling-chamber. Fig. 5 is a sectional plan showing the steam and water distributing valve and float arrangements, one float and valve connection being in section. Fig. 6 is an enlarged sectional view of the distributing-valves and their connections. Fig. 7 is

a diagrammatic view of the complete system, 50 some of the parts being displaced for convenience of illustration.

In carrying our invention into effect we employ a combination vessel having an upper cylinder or tube-chamber A, with an annular 55 settling external casing C surrounding it, and having immediately beneath a condensed-water receiver or chamber B. Within the upper cylinder we arrange a number of brass or other suitable metal tubes D, one end of 60 each tube being secured to the tube-plate E, so as to open into the steam-entrance pocket or chamber F, while the other end of the tube communicates through the opposite portion of the tube-plate directly into the lower 65 cylinder B. Around the tubes water is allowed to circulate, entering from the branch G and leaving by the hot-water pipe H³ to feed the boiler or for other purposes where hot water is required. Beneath the delivery ends of the 70 tubes in the lower vessel is placed a sparger pipe or pipes M for spraying water onto the issuing steam should any not be condensed in passing through the tubes. The sparger-pipes are connected with a water-distributing valve, 75 which is automatically controlled by the action of a float H, carried within the lower vessel B. To remove the air from the chamber and to further assist condensation, a steam-operated air-ejector of any suitable form is 80 arranged at K, or any ordinary air-pump or the like may be employed for exhausting the air. Within the lower cylinder B are placed two floats H H', one float, H, being provided for regulating the admission of steam by 85 means of an equilibrium or other valve L to supply a feed-pump which draws its feed from the lower chamber B' and also for regulating the steam for working the ejectors. The other float, H', regulates the supply of condensing- 90 water to the sparger or spray pipes M. The float-arms h are attached to a spindle N, which passes through suitable stuffing-boxes and is connected to the stem of a water-distributing valve O, which determines the quantity of 95 water that is to be delivered to the sparge-pipes M, the action of the float being such that when the level of the water in the lower

vessel B falls the float movement opens the water-supply valve and an increased quantity of water is delivered to the sparger-pipes to facilitate condensation. At the same time 5 the supply from the steam-distribution valve L increases the action of the air-ejector for the same purpose of greater condensation; but when the water-level rises the actions of these valves are reversed, so that steam is 10 admitted to the feed-pump to reduce the water-level in the receiver, while the ejector and spraying devices are partially or entirely stopped for the time.

The valve L is representative of any suitable form of valve which will perform a two-fold function—*i. e.*, of passing steam to the feed-pump when the float rises and of shutting this off and passing steam to the air-ejector when the float falls.

20 To remove the impurities from the exhaust steam, we pass it from the engine or other exhaust into a settling-chamber or separator C. Within this chamber we arrange a series of vanes, ribs, or baffling division-plates P, 25 which prevent a free passage being formed for the steam from its inlet branch R to its outlet branch S. (See Fig. 7.) Thus the steam is caused to pass by a tortuous path and to meet several surfaces of material P, against 30 which may be deposited the impurities, grease and the like, which may be held in solution or carried by the steam. From the outlet S the steam passes to the entrance-pocket F, Fig. 7. Suitable cleaning-out doors T are provided 35 upon the casing, and a grease-collecting or scum pipe U is arranged within the settling-chamber, as shown in Fig. 1, this pipe also serving to allow the condensed steam to escape when a certain predetermined level has 40 been reached.

To keep the impurities from the first receiver or lower well B', a grid-plate B² is employed, or any ordinary filtering media may be placed in position above the drawing-off 45 well B when so desired. Mud-holes or cleaning-doors b' are arranged upon the lower chamber. Instead of passing the steam through the outer jacket, for special conditions we may sometimes pass the water from 50 the feed-pump through the jacket before it enters the boiler.

The connections and arrangements of pipes between the water-distribution valve, the spraying-pipes, cold and hot water supply, 55 also between the steam-valve and the pump and ejector, may be varied to suit any par-

ticular requirement without departing from the features of our invention.

Having now described our invention, what we claim as new, and desire to secure by Letters Patent, is—

1. In combination, chamber A having condensing-pipe D therein, the inlet and outlet from the chamber A for the cooling-water, the chamber B for the water of condensation and into which the pipes D discharge, the spray-pipe located within chamber B across the outlets of the pipes D for condensing the steam issuing therefrom, a water-valve for controlling the supply to the spray-pipe, a steam-valve controlling a feed-pump, and floats in the chamber for opening the steam-valve when the condensation-water rises in the chamber and for opening the water-valve, when the water falls, to supply the spray-pipe, substantially as described.

2. In combination, the chamber A, the condensing-pipes D therein, said chamber having the inlet and the outlet for the cooling-water, the chamber B for the water of condensation and into which the pipes D discharge, the spray-pipe in the chamber B across the outlets of the pipes D, the air-ejector connected to the chamber B, a water-valve for controlling the spray, a float in the chamber B controlling said valve, a steam-valve controlling the air-ejector in one position and a feed-pump in another position, and a float in the chamber for controlling the position of the steam-valve, substantially as described.

3. In combination, the chamber A having condensing-pipes D therein, the condensation-chamber into which the pipes D discharge, the settling-chamber C surrounding the chamber A, the inlet for the steam to said chamber, the entrance-pocket F for the pipes D and the connection from the chamber C to the entrance-pocket F, substantially as described.

In witness whereof we have hereunto set our hands in presence of two witnesses.
